Inventor:

UNITED STATES PATENT OFFICE.

FRANK C. DUDLEY, OF BROOKLYN, NEW YORK.

CLINICAL THERMOMETER.

1,145,675.

Specification of Letters Patent.

Patented July 6, 1915.

Application filed October 17, 1914. Serial No. 867,049.

To all whom it may concern:

Be it known that I, FRANK C. DUDLEY, a citizen of the United States of America, residing at Brooklyn, in the county of Kings and State of New York, have invented certain new and useful Improvements in Clinical Thermometers, of which the following is a specification.

My invention relates to an improved clinical thermometer.

One of the objects of the invention is to provide means in a thermometer of this kind whereby the mercury tube or stem may be immersed in liquid antiseptic when the thermometer is not in use.

Another object is to provide means to prevent leakage of the antiseptic solution when the thermometer is carried in the pocket or lies on a table or the like.

It is also an object of the invention to so construct the thermometer, that the antiseptic will be visible, thus enabling the user to determine when a new supply is necessary.

A further object of the invention is to provide a convenient and compact device, which may be readily assembled and disassembled for cleaning purposes, and in which the graduated markings on the mercury tube cannot be effaced by the solution employed.

The invention comprises the several features and combinations hereinafter more fully described, the novelty being pointed out in the appended claim.

The preferred embodiment of the invention is illustratively exemplified in the accompanying drawing, in which—

Figure 1 is an elevational view of the improved thermometer; Fig. 2 is a longitudinal sectional view, the mercury tube being shown in elevation; Fig. 3 is an enlarged vertical sectional view of the upper portion of the thermometer. Fig. 4 is a transverse sectional view taken on the line 4—4 of Fig. 3 and looking in the direction of the arrows; Fig. 5 is a similar view taken on the line 5—5 of Fig. 3, and looking in the direction of the arrows; and Fig. 6 is a similar view taken on the line 6—6 of Fig. 3, and looking in the direction of the arrows.

Referring to the accompanying drawing, 10 denotes the exterior casing which is preferably enlarged at 11 to provide a convenient handle, and has its body portion 55 provided with elongated apertures or openings 12, and one end permanently open at

13. Designed to telescope with the exterior casing 10 and coaxial therewith, is the transparent antiseptic container or tube 14 which, as shown in the drawing, is preferably made 60 of glass. By this construction, the antiseptic 15 (usually alcohol) placed in the tube 14 is visible through the openings 12 in the outer casing 10, the latter being preferably of nickel or any other suitable metal 65 pleasing to the eye.

The inner periphery of the enlarged head 11 of the tube 10 is threaded to receive the externally threaded knob 16 carried at one end of the mercury tube 17. The latter is 70 provided with the indication graduations 18 preferably of cement or a similar material which will not be dissolved or effaced by the antiseptic solution 15 within the tube 14.

In order to prevent leakage of the fluid out of the tube 14 I provide the following construction, reference being had more especially to Fig. 3 of the drawing. Approximately intermediate its ends the enlarged 75 portion 11 of the tube 10 is provided with an interior shoulder 19 the surface of which is intended to be flush with the upper edge of the glass tube 14. Resting upon this shoulder is a flexible septum 20 preferably 80 of rubber. As indicated more particularly in Fig. 6, the septum is provided with the divergent slots or cuts 21 so that when the mercury tube 17 is protruded through the septum the material of the latter will yield 85 sufficiently to allow passage of the tube, but will also have a tendency to hug the tube 17, extend inwardly into the tube 14, and thus act to prevent leakage of fluid past the septum.

To clamp the septum in position I place immediately over its periphery a metal ring or washer 22 one surface of which is crimped or roughened as shown in Fig. 5, for the purpose of obtaining a good purchase 100 against the septum 20. Taking against the ring 22 is an externally threaded nut 23, the threads of which engage the threads formed on the interior of the enlarged portion 11 of the tube 10. By screwing home 105 the nut 23, the septum 20 is compressed against the seat or shoulder 19 through intermediary of the crimped ring 22.

When it is desired to use the thermometer, the knob 16 is turned in the proper direction 110 until the threads thereon are disengaged from the threads of the enlarged head mem-

ber 11, and then the mercury tube is drawn out of the glass tube 14. After use the mercury tube is passed through the septum 20 back into the antiseptic solution, and the 5 knob 16 again screwed into position.

For the purpose of disassembling the device when the parts are in the position shown in Fig. 3, the mercury tube is removed in the manner just above explained, thereafter the 10 nut 23 is taken out by means of a spanner or other appropriate tool, the ring 22 and septum 20 removed, and then the glass tube 14 may be lifted out, cleaned and refilled if desired. To assemble the device, the glass 15 tube is inserted in the metallic exterior casing 10, the septum 20 and ring 22 placed in position, and the nut 23 then screwed home. Thereafter the mercury tube is reinserted and screwed down. When the mercury tube 20 is in the position indicated in Fig. 3, leakage of fluid past the septum 20 is practically impossible, and the entrance of foreign substances into the glass tube 14 is also obviated. Moreover, as the mercury tube is 25 drawn out for use, the surface thereof will

be cleaned to a considerable extent by contact with the tightly embracing edges of the rubber septum 20.

What I claim is:—

In a clinical thermometer, the combination of an exterior metal casing, provided with apertures in its body portion and having an enlarged end threaded interiorly, a shoulder within said casing and adjacent one end of said threads, a transparent tube 30 within said casing and having its open end flush with said shoulder, a slotted flexible septum resting on said shoulder and the open end of said tube, means for clamping said septum in position, said means comprising a crimped washer engaging the septum and a nut taking against said washer, and a mercury tube having a threaded knob 35 designed to engage the threads on the casing.

In testimony whereof I have affixed my 40 signature in presence of two witnesses.

FRANK C. DUDLEY.
